UNITED STATES PATENT OFFICE.

DAVID LEWIS REESE, OF LOS ANGELES, CALIFORNIA.

OIL-BURNER.

1,188,830.

Specification of Letters Patent. Patented June 27, 1916.

Application filed October 1, 1915. Serial No. 53,654.

To all whom it may concern:

Be it known that I, DAVID LEWIS REESE, a citizen of the United States, residing at Los Angeles, in the county of Los Angeles and State of California, have invented certain new and useful Improvements in Oil-Burners; and I do hereby declare the following to be a full, clear, and exact description of the invention, such as will enable others skilled in the art to which it appertains to make and use the same.

My invention relates to new and useful improvements in oil burners and more particularly to that class adapted to be used for burning crude oil and my object is to provide means for introducing air or steam around the burner and commingling the same with the oil at a point beyond the end of the burner.

A further object is to so construct the burner that the point of combustion will be extended beyond the head of the burner. And a further object is to provide means for increasing or decreasing the size of the flame at the end of the burner as occasion may require.

Other objects and advantages will be hereinafter set forth and more particularly pointed out in the accompanying specification.

In the accompanying drawings which are made a part of the application, Figure 1 is a plan view of the burner. Fig. 2 is a central longitudinal sectional view, as seen on line 2—2 of Fig. 1, and Fig. 3 is a transverse sectional view through the burner head, as seen on line 3—3 of Fig. 2.

Referring to the drawings in which similar reference numerals designate corresponding parts throughout the several views, 1 indicates the oil conveying pipe which is attached in any suitable manner to a supply tank, or the like, (not shown), said pipe terminating at one end in a nozzle 2, the exterior wall of which is beveled to form a substantially frusto-conical structure. Adjacent the nozzle end of the pipe 1 is an integral peripheral wall 3 with which is formed integral a sleeve 4, said sleeve being exteriorly threaded to receive a coupling 5, and coöperating with said coupling is a pipe section 6 for the reception of air or steam. The opposite end of the pipe section 6 is engaged with a hollow cross head 7 which cross head is provided with inlet ports 8 through which steam or air is introduced

into the pipe section 6 and around the oil pipe 1, the outer end of the cross head being closed by threading a nut 9 on to the oil pipe 1 and into the end of the cross head.

The air or steam is permitted to leave the chamber between the oil pipe 1 and pipe section 6 through ports 10 in the wall 3, said air or steam after passing through the ports entering the chamber 11 of a collar 12, said collar having a head 13 at its outer end through which is formed an opening 14, the wall of which is tapered coincident to the taper of the nozzle 2, and by providing threads interiorly of the end of the collar 12 and exteriorly of the sleeve 4, the head may be adjusted outwardly or inwardly to increase or decrease the space between the beveled walls of the head and nozzle, thereby increasing or decreasing the size of the flame at the end of the nozzle.

The nozzle is so arranged as to project beyond the outer end of the head 13 so that the flame will always be beyond the head, thereby eliminating any possibility of carbonization within the head and thus leaving a free passage for the air or steam.

It will likewise be seen that by emitting the air or steam in the rear of the end of the nozzle, suction will be created in the oil pipe to cause the oil to properly feed regardless of the consistency of the oil.

It will likewise be seen that the burner can be very cheaply constructed, and in view of the fact that the size of the flame can be increased or decreased, it can be used with stoves, furnaces or fire boxes of various sizes.

Having thus fully described my invention what I claim as new and desire to secure by Letters Patent of the United States is:—

A burner comprising a pipe section, a hollow cross head attached to one end of the pipe section and having oppositely disposed inlet ports for the reception of steam, an oil conveying pipe extending longitudinally through the pipe section and cross head and beyond the ends thereof, one end of said oil conveying pipe being threaded and the opposite end being tapered to form a nozzle, a nut engaging the threaded end of the oil conveying pipe and threaded into one end of the cross head to form a closure therefor, a peripheral wall integral with the oil conveying pipe, a sleeve integral with the outer edge of said wall, said wall having ports therethrough midway between the oil

pipe and sleeve, a coupling connecting said pipe section and sleeve, a collar adjustably secured to said sleeve and a head at one end of the collar having a tapered opening to coöperate with the tapered wall of the nozzle.

In testimony whereof I have signed my

name to this specification in the presence of two subscribing witnesses.

DAVID LEWIS REESE.
